UNITED STATES PATENT OFFICE.

HARRY H. DANIELS, OF WINTHROP, MASSACHUSETTS.

STAMP-AFFIXING MACHINE.

Application filed November 21, 1918. Serial No. 263,600.

To all whom it may concern:

Be it known that I, HARRY H. DANIELS, a citizen of the United States, and resident of Winthrop, county of Suffolk, Commonwealth of Massachusetts, have invented an Improvement in Stamp-Affixing Machines, of which the following description, in connection with the accompanying drawings, is a specification, like characters on the drawings representing like parts in each of the several views.

This invention relates to stamp affixing machines of a type adapted to hold a supply of stamps such as postage stamps provided in ribbon form and made up into a roll, and to feed out and apply the same as required for use. The present type of machine is also one adapted to apply moisture to the surface to receive the stamp just in advance of the laying of the stamp thereon, and is equipped with a roller for applying the stamp to the moistened surface, which roller is also the instrumentality operative for feeding the stamps from the roll to the applying point. A prime object of the invention is to provide a device of this character exceedingly simple in construction but efficient and reliable in operation and having no fragile or delicate parts apt to get out of order or cause trouble in use. One important feature of the invention consists in improved means for feeding the stamps from the roll to the applying point, this consisting in a slidable plate adapted to grip the stamp ribbon frictionally on the perforation line, into an angular corner where the stamp is held frictionally as the plate is slid forward positively by suitable operating means preferably operated by the applying roll, thus dispensing with delicate and fragile spring fingers which have heretofore been usually employed for engaging the perforations in the stamp ribbon to feed the same forward. According to a further feature of the invention I provide a water container equipped with a moisture applying wick to engage the stamp receiving surface some little distance in advance of the applying roll and yieldable relatively to said roll upon engagement with the stamp receiving surface so that in use it is not necessary for the operator to bring the surfaces of the applying roll and the wick into precisely the plane of the receiving surface before the device can be used to apply the stamp. A further object is to provide improved simpli-

fied means for locking the applying roll against further movement after a stamp has been fed out and applied thereby, such means also preferably including provision whereby the roll is automatically released for another operation as soon as lifted from the stamp receiving surface. Another object is to provide improved means for clamping the stamp ribbon adjacent the severing point and in combination therewith improved severing means. Another object is to provide an improved construction and arrangement of parts whereby the machine may be instantly opened up for any necessary attention or inspection, and in combination therewith an improved locking device that embodies exceptional reliability and simplicity. Another object is to provide an improved applying roller of sectional form specially adapted for taking care of irregularities in the stamp receiving surface. Another object is to provide an improved removable and pivotal mounting of the water tank. Another object is to provide improved means for regulating the outflow of water from the tank to the applying wick. A still further object is to provide means adjacent to and co-operative with the stamp roll and its holder whereby the curling tendency is eliminated from the stamp ribbon as it is delivered. The foregoing and other objects and advantages of the invention will more fully appear from the following detailed description, and the distinctive features of novelty will be pointed out in the appended claims.

Referring to the drawings:

Fig. 1 is a side elevation showing the device in operative position;

Fig. 1^a is an elevation of the water tank removed;

Fig. 2 is a detail section on line 2-2 of Fig. 1;

Fig. 3 is a detail plan view showing a part of the top of the water tank and illustrating the means for controlling the flow of water;

Fig. 4 is a fragmentary elevation showing a part of the interior construction including a device for ironing out and eliminating the curl in the stamp ribbon;

Fig. 5 is a side elevation partly of the exterior of the machine and partly broken away to show interior construction;

Fig. 6 is a fragmentary side elevation of the stamp clamping and severing means;

Fig. 7 is a detail front elevation thereof;

Fig. 8 is a side elevation showing the machine opened for inspection or attention;

Fig. 9 is a lengthwise vertical section of the machine;

Fig. 10 is a detail perspective of the applying roll removed and with portions broken away;

Fig. 11 is a face view of a lock tumbler removed;

Fig. 12 is a sectional view of the lock;

Fig. 13 is a perspective view illustrating the stamp feeding slide and parts co-operative therewith; and

Fig. 14 is an elevation illustrative of the feeding slide mechanism.

The frame of the machine comprises a base 10 and an upper housing 11 pivoted thereto at the rear as indicated at 12 so that said housing may be swung upward to a perpendicular position with respect to said base as seen in Fig. 8. The base 10 carries the water tank and the stamp feeding slide mechanism while the upper housing 11 is equipped as a holder for the stamp roll and carries the applying roller and other operative instrumentalities. The stamp applying roller 13 is pivoted at 14 to the lower forward portion of the housing 11 and is equipped with gearing connections as later described to operate the slide device for feeding out the stamp ribbon. In accordance with my invention this roll 13 consists in a series, illustratively shown as five in number, of resilient ring sections 15 of soft rubber or the like, these ring sections being individually mounted on a metallic or like core 16 which is equipped with spacing ribs 16^a adapted to hold the respective ring sections in position and preferably spaced slightly apart, this slight spacing apart of such roller sections permitting a more free individual yielding and adaptation thereof to any irregularities that may be presented in the stamp receiving surface. Thus the proper functioning of the applying roll for feeding out and pressing down the stamp is insured even though the backing against which the device operates may be more or less uneven as often results from the variable bulging produced in the corner of an envelope by the folded papers therein. In accordance with my invention improved means is provided whereby the hinged top housing 11 may be locked to the base 10 in a manner so as to be secure against casual tampering. For this purpose the base is equipped with a fixed hook member 17 and the housing 11 is equipped with a swinging hook member 18 to co-operate therewith pivoted thereto at 19. This hook member which is in the form of a curved lever arm has at an intermediate point a forward projection 20 which is adapted to co-operate with the several ring discs 21^a of a tumbler

combination lock 21. The discs 21^a are each formed with a radial slot 21^b and when all these slots are in register the projection 20 may be pressed thereinto releasing the hook 18 and permitting the top housing 11 to open. The lock 21 is equipped with a usual graduated face 21^c equipped with a knurled operating head 21^d, this face and head being exposed at the side of the machine and the lock being bodily removable for changing the combination or other attention by removing a transverse cotter pin 21^e passed through the stem thereof, in a manner that will be readily understood. The lever by which the hook 18 is carried is equipped with a tail portion 18^a which is engaged by one end of a tension spring 18^b anchored to the housing in a manner tending to hold the hook 18 in locked engagement with the hook 17. The lever tail portion 18^a is formed with an arcuate rear edge 18^c which is engaged by the end of a slide 22 slidably guided on a disc 23 said disc constituting a removable side of the stamp roll holder. The housing has fixed thereto a pin or post 24 at the center of the stamp roll cavity and constituting an axis on which the stamp roll is mounted to turn. This pin is provided with a head 24^a with a reduced neck just back thereof and the slide 22 is formed with a slot 22^a of a size to fit said neck but be held by the head 24^a, this slot being opposite said head when the slide 22 is in position to lock the cover disc 23 against removal. The slot 22^a merges into a larger disc opening 22^b toward the outer end of the slide 22 and in position to register with the head 24^a when the slide 22 is pressed forward. For actuating the slide 22 it is equipped with a head 22^c projecting through a radial slot 23^a of the disc 23. Since the inner end of the slide 22 normally rests against the curved edge 18^c of the hook lever 18, it follows that the spring 18^b will normally hold the slide 22 pressed outward and thus at once hold the hooks 17, 18 in interlocking relation and also hold the slide 22 in position to lock the cover disc 23 in place, while upon pressing the slide 22 inward by means of the head 22^c, it is caused to release the cover disc 23 and at the same time press the hook 18 out of engagement with the hook 17 to permit opening of the housing, all this occurring only after the combination lock has been actuated for the combination to which it is set. It is to be specially noted that with the present construction the projection 20 does not automatically snap into the slots 21^b of the lock tumblers as soon as they come into register, but that a further positive actuation of the head 22^c is necessary. Thus possibility of tampering with the lock is minimized since as there is no click or other automatic indication when the proper opening combina-

tion has been reached, the operator can only open the device by making a further separate movement of the head 22° after the combination has been reached and without 5 any other auxiliary indication.

In accordance with my invention moisture is supplied by a wick 25 which is yieldingly mounted to press against the receiving surface just in advance of the applying roll 13. 10 This wick is carried at the end of a long flat forward projecting portion 26^a of a water tank 26. This tank is mounted between lugs 10^a, 10^b which constitute a bifurcated rearward extension of the base 10 and to the 15 upper portion of which the housing pivot 12 is applied. Means is provided whereby the water tank is yieldingly held on definite pivots so as to be capable of easy removal and replacement. For this purpose the base 20 of the tank is formed with depressed socket points 27 at opposite sides and these are engaged by ball heads 28 carried at the lower ends of spring plates 29 fixed to the lugs 10^a, 10^b. Thus the tank is permitted 25 free limited swinging movement the extent thereof being determined by the upper portion thereof coming against the adjacent wall 10^c of the base and it is normally spring pressed downward by a leaf spring 28 secured 30 to the base and pressing against the projecting portion 26^a. The tank is provided with a suitable filling opening normally closed by a screw plug 28^b. Since it is important that water be delivered to the 35 wick 25 only in sufficient quantity for requirements, I preferably provide means whereby the delivery of water to the wick may be adjusted and varied as required. I accomplish this in the preferred embodiment 40 shown by varying the vent to the tank by means of a swinging plate 30 pivoted to the top of the tank at 31 and having a series of holes 32 of diverse sizes therein and adapted to be selectively brought into register with 45 a hole in the top of the tank.

The stamp roll R is fitted on the post 24 in a holder cavity 33 provided therefor in the top housing and it has at its bottom a delivery mouth 34 through which the stamp 50 ribbon r is drawn. This mouth as shown is relatively narrow, i. e., only large enough to afford easy clearance for the stamp ribbon passing therethrough and the stationary wall of the housing at the front side thereof 55 is brought up to constitute an abrupt edge 35 around which the stamp ribbon is drawn at an abrupt angle and flexed oppositely to the direction of the curl therein as it comes from the roll so that this curling tendency 60 is substantially eliminated. This drawing out movement of the stamp ribbon is accomplished by means of a slide plate 36 guided to operate in the bottom of the base 10 being held in place by rails 36^a at the 65 sides of the base, and fitted under a station-

ary slotted plate 37 secured to the base and with which the plate 36 is associated in a manner so as to permit endwise sliding movement but prevent displacement otherwise. The slide plate 36 is engaged by a 70 tension spring 38 anchored to the base and tending constantly to draw said slide to its backward limit of movement. Fitted to cooperate with the slide 36 and movable on plate 37 is a secondary stamp clamping slide 75 39 engaged by a light tension spring 40 anchored to the base and tending constantly to draw said slide backward so that its rear edge will grip or clamp the stamp ribbon against an upright portion of the slide 36 80 as indicated at 36^b. The slide 36 is moved forward by operative connections from the roll 13 for feeding out a stamp whenever said roll is drawn over a receiving surface and then released to be drawn backward by 85 the spring 38 in readiness for another movement. For this purpose the slide 36 is equipped with an upstanding prong 41 engageable by a two lobed cam wiper 42 which is pivoted to the housing at 43 and has rigid 90 therewith a pinion 44 which through an intermediate gear 45 pivoted to the housing is driven from a pinion 46 rigid with the roll 13. It is to be noted that the pinions 44, 46 are the same size and thus it follows that 95 one of the two cam lobes 42 will be moved forward to actuate the prong 41 at each half rotation of the applying roll and as seen in Fig. 5 said lobes are of such a form that they will then release the prong 41 at the 100 end of a complete forward movement of the slide 36 to permit it to be drawn backward by its spring. The slide 36 is also preferably equipped with a prong 47 at its rear 105 constituting a stop with which a cam lobe 12 engages to stop the cam and lock it against further movement after it has completed a forward feeding movement of the slide, and it is not released until the machine is picked up and the roll 13 freed. It 110 is to be noted that the cam lobes 42 are of some little larger diameter than the applying roll and this thus causes an accelerated advance of the feed slide 36 making some little slack in the stamp ribbon between the 115 clamping point thereof on the slide and the applying roll, this slack being taken up by the final pull imparted by the roll which severs the stamp after the clamp is engaged as hereinafter explained. From the clamping point 36^b the stamp ribbon passes between the slide plate 36 and the secondary slide 39, over a severing edge 48 which is mounted just behind the applying roll. This severing edge is preferably tapered 120 downward and backward towards each side from a central point to facilitate the severing action. Said edge is carried by a depending projection of a lever 49 fulcrumed to the housing at 50 and having a depending 125 130

bell crank beak 51 operative to clamp the stamp ribbon against a forward extension of the stationary plate 37 by pressure exerted on the severing edge 48 on the downward pull of the stamp ribbon thereagainst in severing the stamp, and thus the stamp ribbon is clamped securely just back of the severing point as the severing occurs. This prevents more than one stamp from being drawn out at once and hence there can be no uncounted stamp. For preventing any backward movement of the stamp ribbon within the machine when it would be otherwise free to do so I provide a swinging dog 52 pivoted on an intermediate portion of the pin fulcrum 50 to constitute a back latch clip, this dog having a tail portion thereof engaged by the coil spring 53 mounted on the pin 50 and stationarily anchored at its other end. This back latch clip therefore is always pressed downward in position to engage the stamp ribbon a short way back of the severing edge and in a manner so as to be drawn downward into clamping engagement with the stamp ribbon upon any tendency to backward movement thereof while permitting relatively free forward movement thereof. I preferably equip the machine with a counter to indicate and record the number of stamps given out. This counter indicated at 54 is mounted on a shelf 55 provided on an interior portion of the housing and it is operated by a gear 56 shown as rigid with the pinion 44 and the cam lobes 42. The housing is provided with a suitable sight opening 57 for reading this counter. It is to be noted that the present mechanism eliminates the necessity for light and fragile spring fingers which have heretofore been considered necessary for engaging the perforation line in a stamp ribbon to feed the same forward. When the stamp ribbon is drawn out to feed a stamp by the action of the applying roll the secondary slide 39 will be moved forward to some extent against the tension of its spring at the same time the main slide 36 is moved forward and as a perforation line is reached in the stamp ribbon this weakened line will bend around the edge of the secondary slide 39 stopping the further movement of the stamp ribbon past the same, it being understood that the parts are so proportioned that this perforation line does not come into register with the edge of said plate until approximately the end of the feed movement and hence the abrupt folding of the weakened perforation line around this edge is only required to take care of small variations in distance between perforation lines. I am aware that the invention may be embodied in other specific forms without departing from the spirit or essential attributes thereof, and I therefore desire the present embodiment to be considered in all re-

spects as illustrative and not restrictive, reference being had to the appended claims rather than to the foregoing description to indicate the scope of the invention.

Having described my invention, what I claim as new and desire to secure by Letters Patent is:

1. Stamp affixing mechanism, comprising a magazine stamp holder adapted to hold a stamp ribbon, an applying member, an intermediate severing device, and means associated with said severing device and operated by the stamp ribbon when placed under tension for clamping the stamp ribbon just back of the severing point. 80

2. Stamp affixing mechanism, comprising a magazine stamp holder, an applying roll, an intermediate severing device, and means connected with and operated by said severing device for clamping the stamp ribbon just back of the severing point. 85

3. Stamp affixing mechanism, comprising a magazine stamp holder, an applying roll, a movably mounted severing device, and a clamp connected with said severing device 90 to be actuated thereby for clamping the stamp ribbon back of the severing point.

4. Stamp affixing mechanism, comprising a magazine stamp holder, an applying member, a severing edge having a central projecting portion with side portions receding therefrom, said severing edge having a pivotal mounting, and a clamp associated therewith and operated thereby for clamping the stamp ribbon as the severing takes place. 100

5. Stamp affixing mechanism, comprising a magazine stamp holder, an applying member, a severing edge pivotally mounted adjacent said applying member and having connected therewith a clamp adapted to 105 grip the stamp ribbon back of the severing point as the severing occurs.

6. Stamp affixing mechanism, comprising a base equipped with means for controlling the feeding out of the stamps and with a 110 severing device, and an upper housing pivoted at its rear to said base and equipped with a magazine stamp holder and with an applying roll.

7. Stamp affixing mechanism, comprising 115 a base equipped with means for controlling the feeding out of stamps and with a severing device, an upper housing movably engaged therewith equipped with a magazine stamp holder and with an applying roll, 120 and means for locking said housing to said base.

8. Stamp affixing mechanism, comprising a base equipped with means for controlling the feeding out of stamps and with a severing device, an upper housing pivoted there-to equipped with a magazine stamp holder and with an applying roll, said stamp holder having a detachable side closure, and a single locking device adapted to lock said hous- 130

ing in assembled relation with said base and also to lock said side closure against removal.

9. Stamp affixing mechanism, comprising a base equipped with means for controlling the feeding out of stamps and with a water tank, an upper housing pivoted thereto for opening movement and equipped with a magazine stamp holder and an applying roll, said stamp holder having a removable closure member, a single locking device arranged to lock said closure member in place and also to lock said housing in operative relation with said base, and a combination tumbler device controlling said locking device, said locking device constructed and arranged to require a manual actuation separate from the actuation of said tumbler to release the same.

10. Stamp affixing mechanism, comprising a magazine stamp holder adapted to hold a stamp ribbon, and an applying roll associated therewith adapted for pressing the stamps onto a receiving surface consisting 25 in resilient elements separately mounted and spaced from one another.

11. Stamp affixing mechanism, comprising a magazine stamp holder adapted to hold a stamp ribbon, and an applying roll associated therewith adapted for pressing the stamps onto a receiving surface consisting in a plurality of resilient rings mounted in spaced apart relation on a central core.

12. Stamp affixing mechanism, comprising a magazine stamp holder adapted to hold a stamp ribbon, and an applying roll associated therewith adapted for pressing the

stamps onto a receiving surface composed of a plurality of resilient ring members mounted side by side.

13. In a stamp affixing machine, an applying roll adapted for pressing stamps onto a receiving surface consisting in a plurality of resilient rubber rings mounted side by side in spaced apart relation.

14. Stamp affixing mechanism, comprising a magazine stamp holder, an applying roll receiving said stamp ribbon from the holder, and a water tank pivoted in proximity to said applying roll on yieldable pivot members so as to be capable of easy removal, said tank having a wick arranged to moisten a receiving surface slightly in advance of said roll.

15. Stamp affixing mechanism, comprising a magazine stamp holder, an applying roll, and a water tank having a forward extension equipped with a wick adjacent said applying roll, said tank having a rearward body portion mounted on yielding pivots so as to be capable of easy removal.

16. Stamp affixing mechanism, comprising a stamp applying member, and a tank equipped with a wick mounted adjacent said applying member, said tank having a vent 65 passage with a movable plate fitted thereover and having diverse sized vent holes for selective register with said vent passage to determine the amount of water delivered to said wick.

In testimony whereof, I have signed my name to this specification.

HARRY H. DANIELS.
